UNITED STATES PATENT OFFICE.

UMBERTO A. VALENTE, OF BROOKLYN, NEW YORK.

METHOD OF ATTACHING HANDLES AND THE LIKE.

1,416,532.

Specification of Letters Patent. Patented May 16, 1922.

Application filed May 21, 1920. Serial No. 383,186.

To all whom it may concern:

Be it known that I, UMBERTO A. VALENTE, a citizen of the United States, residing at Brooklyn, in the county of Kings and State 5 of New York, have invented new and useful Improvements in Methods of Attaching Handles and the like, of which the following is a specification.

This invention relates to methods of 10 curing parts, such as handles and feet, to a vessel, by casting the same directly in interlocking securement to parts especially formed on the vessel or embodied thereby; and further, it relates to articles embodying these 15 mentioned features of construction.

Some of the objects of the invention are: to produce different articles, such as casserole or the like, with necessary handles and feet, in such a manner as to realize a more 20 effective attachment or interlock between the handles and feet, and the vessel; to effect the attachment of handles, feet, etc., in a more facile and economical manner.

In the drawing forming a part of this application:

Figure 1 is a side elevation of a casserole with handles and feet attached in accordance with the present invention:

Figure 2 is an elevation of a fragment of 30 the outer vessel of the casserole and showing some of the wings as formed thereon:

Figure 3 shows a mold positioned with respect to the wall of the vessel and wings formed thereon for the casting of a combined handle and foot in securement with 35 said wings:

Figure 4 is a vertical sectional view illustrating the application of the handle and integral foot:

Figure 5 is a transverse sectional view on 40 the line 5—5, Figure 4.

Referring now to Figure 2 of the drawing, it will be seen, that the wall 10 of the outer vessel 11 of the casserole 12, is provided with wings 13. The wings 13 are struck up from the wall 10. The wings as shown are produced in pairs. Each wing is preferably bent to provide different relatively disposed parts. The wings of each 50 pair oppose each other. In striking up the wings, apertures 14 are necessarily produced in the wall 10. An aperture 14 occurs immediately adjacent each wing 13. Pairs of wings are arranged in vertical alinement,

and handles are preferably attached to the 55 pairs of wings so arranged. Whereas, for the attachment of feet, a pair of wings near the bottom of the wall 10, serves very effectively.

For attaching the handles, feet, etc., to the 60 vessel 11, use is made of a mold 15, shown in Figure 3. The molten metal from which the parts to be attached, is to be formed, is poured into the mold. The liquid-like metal finds its way to the wings 13, and part of it 65 enters the apertures 14, beside the spaces defined by the said wings. The setting of the metal causes an interlock between the formed part and the wings as will be readily understood. Different molds of course are 70 used for the formation and the attachment of different parts. The attachment of parts to a vessel in this manner may be accomplished very easily and economically. The use of rivets and the like and solder is ob- 75 viated. A better and a more attractive job will be the result of the practice of the present invention—experience taught this.

In the present application of the invention the combination handle and foot 16 is attached at each end of the vessel 11, and a foot 17 is arranged at each side of the vessel 11 near the bottom thereof.

What is claimed is:

1. A method of casting by means of which 85 one metallic object is to be connected to a second object characterized by employing upstruck means on the last named object, and subsequently attaching a mold to said object, which mold will engage the same at 90 points adjacent the points of disposition of the upstruck means, and in pouring fluid metal into said mold to cause said metal to engage said upstruck means.

2. A method of completing an article 95 wherein one metallic object is connected to a second object characterized by forming upstruck means integral with said second object, and subsequently attaching a mold to said second object, which mold will engage 100 said object at points adjacent the points of disposition of the upstruck mean; and in pouring a fluid metal into said mold to cause said metal to be formed in engagement with said upstruck means.

In testimony whereof I have affixed my signature.

UMBERTO A. VALENTE.
